Fig. 1

Fig. 2

Fig. 3

FIG. 1 is an elevated front left perspective view of the file cart, showing one of the tambour bin covers slid open and the other cover slid partially open, exposing the file bin interior.

FIG. 2 is a plan view, showing the tambour covers in the FIG. 1 position.

FIG. 3 is a slightly elevated three-quarter rear left view, showing the tambour covers slid closed, concealing the file bin interior.

I claim:

The ornamental design for a file cart with tambour covers, substantially as shown and described.
